UNITED STATES PATENT OFFICE.

WILLIAM H. WRIGHT, OF BRISTOL, CONNECTICUT, ASSIGNOR TO THE
E. INGRAHAM COMPANY, OF SAME PLACE.

SASH FOR CLOCK-DIALS.

SPECIFICATION forming part of Letters Patent No. 614,523, dated November 22, 1898.

Application filed July 25, 1898. Serial No. 686,781. (No model.)

To all whom it may concern:

Be it known that I, WILLIAM H. WRIGHT, of Bristol, in the county of Hartford and State of Connecticut, have invented a new Improvement 5 in Sashes for Clock-Dials; and I do hereby declare the following, when taken in connection with the accompanying drawings and the letters of reference marked thereon, to be a full, clear, and exact description of the same, 10 and which said drawings constitute part of this specification, and represent, in—

Figure 1, a view in front elevation of a clock-dialsash constructed in accordance with my invention; Fig. 2, a sectional view thereof; Fig. 3, an enlarged sectional view.

My invention relates to an improvement in sashes for clock-dials of the class of sashes commonly known to the trade as "French" sashes, the object being to produce of the 20 type mentioned a sash which shall not only be very much cheaper than the French sash of commerce, but which shall be more convenient in use and present fully as attractive and elegant an appearance.

With these ends in view my invention consists in a sash for clock-dials having certain details of construction and combinations of parts, as will be hereinafter described, and pointed out in the claim.

In carrying out my invention I form by casting or otherwise a heavy annular sash-band A, which will ordinarily be produced with more or less elaborate ornamentation in relief. I secure this band by its rear face to the forward edge of an annular sheet-metal sash-flange B, which extends rearward at a right angle to the vertical plane of the band, which, together with the said flange, forms the sash proper. I may secure the flange and ornamental band together in any desired manner. As shown, the rear face of the band is formed with a very narrow shoulder a, which is encircled by the extreme forward edge of the flange, as clearly shown in Fig. 3, the flange and band being soldered, screwed, riveted, swaged, or otherwise secured together, or, if desired, the band may be cast upon the forward edge of the flange. As herein shown, the glass C is laid against the

inner face of the band and held in place by 50 means of a light ring D, secured within the forward edge of the flange.

The dial E, which may be of any approved construction, is itself mounted in the inner edge of the beveled mat F, struck up from 55 light sheet metal and preferably made highly ornamental. The said mat F is secured to the said sash-flange B by means of a hinge G of any suitable construction. I should also mention that the mat is formed with a slightly- 60 beveled shoulder F', which is made small enough in exterior diameter to permit the sash-flange B to readily pass over it. As this is not a friction fit like that relied upon in a French sash to hold the sash in its closed position with respect to the mat, I provide fastening means which are here shown to consist of a retaining-point H, formed in the shoulder F' of the mat, and a retaining-socket H', formed in the sash-flange B; but these fastening devices may be replaced by any other 65 suitable construction. 70

By forming the sash-band and sash-flange of the sash independently of each other I avoid the expense of turning a cast sash-flange 75 down in a lathe, and am also enabled to produce in soft metal a sash-band more ornate than it is practical to make in hard metal with an integral sash-flange. I also avoid the necessary turning of the exterior shoulder of 80 the mat required to secure a friction fit between it and the sash-flange. My improved sash is therefore not only very much cheaper to produce than the ordinary French sash, but it may be made even more elegant in appearance and is vastly more convenient in use.

Having described my invention, what I claim is—

In a sash for clock-dials, the combination with an independently-formed ornamental 90 sash-band, of a sheet-metal sash-flange formed independently of the said sash-band, secured by its forward edge to the rear face thereof and extending rearwardly therefrom at a right angle to the plane thereof, the said band and 95 flange together forming the sash, a dial, a sheet-metal mat in which the dial is mounted and which is formed with an external shoul-

der of smaller diameter than the said sash-flange, a hinge for securing the sash to the said dial-mat, and means applied to the said mat and the said dial-flange for securing the 5 sash in its closed position with respect to the mat, substantially as set forth.

In testimony whereof I have signed this

specification in the presence of two subscribing witnesses.

WILLIAM H. WRIGHT.
